Primary Examiner — Leanne Was-Englehart*Assistant Examiner* — Molly Loch(74) *Attorney, Agent, or Firm* — Holtz, Holtz & Volek PC(57) **CLAIM**

The ornamental design for a watch case as shown and described.

DESCRIPTION

FIG. 1 is a front, right side, bottom perspective view of a watch case showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The broken lines depict portions of the watch case that form no part of the claimed design.
